UNITED STATES PATENT OFFICE

DULCIE McCULLOUGH, OF NEW YORK, N. Y.

SANITARY NAPKIN-SUPPORTING BELT

Application filed July 16, 1928. Serial No. 292,955.

The invention relates to improvements in supporting belts particularly useful in connection with the utility of Kotex, sanitary napkins and like articles of wear.

5 The object of the invention lies in the providing of a single piece or integral belt member of an extensible or elastic material shaped and formed to rest against the body of the wearer adjacent the waist and so disposed as 10 to receive its support at the hip portion thereof, the portions of said belt forming the front and back, thereof being dipped to rest lightly upon the abdomen and back of the body of such wearer, said front and back portions of 15 said belt having attached thereto inextensible tapes, depending therefrom to a suitable length, and carrying at their ends safety pins to which the Kotex or formed sanitary napkin is detachably supported.

20 Another object of the invention resides in the form of the supporting belt, in that the front and back portions of same are of a V-shaped contour arranged to dispose the relative sides of said belt immediately upon the 25 hips of the wearer to eliminate the sag and pull of devices of the type as described, such form of said belt further providing one wherein the ease of wear predominates.

In the following there is described one embodiment of the invention the particular features thereof being more fully set forth hereinafter in the claim.

In the drawings, Fig. 1 is a perspective view of the napkin supporting belt disposed 35 upon the figure of a wearer illustrating the relation of same upon such wearer, and the relation of the supporting tapes to said body when supporting a sanitary means of any kind or nature; Fig. 2 is a face elevation of 40 the supporting belt showing the position thereon of said aforesaid supporting tapes and the attaching safety pins; and Fig. 3 is a vertical sectional view on the line 3—3 of Fig. 2.

45 Similar numerals of reference indicate similar parts throughout the several views of the drawings forming part hereof.

In the drawings, 1 designates the supporting belt composed of extensible or elastic 50 members 2 and 3 attached together at their

respective ends by means of fabric strips 4, said members 2 and 3 being cut in such a manner as to dip toward the attached ends thereof to form the means of disposing said belt from the hips of the wearer, rather than the 55 abdominal and back portions of the body, providing thusly a supporting belt adapted to eliminate all strain or weight from the attaching means carrying the sanitary member.

Said belt 1 has attached or otherwise fastened to said member 2 and 3 thereof front tapes 5 and back tapes 6 carrying at their respective ends the looped ends 7 of safety pins 8 the opening ends of which receive and 60 support the Kotex or other form of sanitary napkin 9.

The invention as described embodies a departure in type and form of like structures and the form thereof may be altered in many 70 ways without departing materially from the scope of same.

What is claimed and desired to be secured by Letters Patent of the United States is:—

A sanitary napkin supporting belt comprising a belt consisting of two members of elastic material attached together at their ends by fabric strips to form V-shaped dips at the front and rear of the belt, a pair of dependent tapes attached to the belt at the 75 front thereof symmetrically disposed with respect to said dip, and a pair of dependent tapes similarly attached to the belt at the rear thereof, each of said tapes consisting of a narrow strip attached to the belt at its ends 80 to form a dependent loop, and safety pins for attachment to the corners of a sanitary napkin, each of said loops being threaded 85 through the looped end of a safety pin.

In testimony whereof I have signed my 90 name to this specification this 14th day of July, 1928.

DULCIE McCULLOUGH.
